INKING EDGES OF SHOE PARTS

Valentine F. Harrington, Newton, Mass., assignor
to B. B. Chemical Co., Boston, Mass., a corpora-
tion of Massachusetts

Application December 5, 1938, Serial No 243,943

14 Claims. (Cl. 91—18)

This invention relates to a method of and machine for applying ink to the edges of a shoe part. The machine shown herein by way of illustration is adapted for applying ink to either the peripheral edges of unassembled shoe-upper parts or the edges of cut-out openings formed therein, the inking action taking place progressively across the part without regard to its contour.

The application of ink, stain, or other coloring or treating material to the edges of a shoe-upper part and particularly to the edges of cut-out openings therein is troublesome and in most factories is carried out by hand, the ink frequently being applied by a pipe cleaner dipped in the coating material. It has been proposed in Letters Patent of the United States No. 1,285,903, granted November 26, 1918, on the application of L. J. Bazzoni, to apply the ink to the edges by coating the whole of the wrong side of the material, which in a leather part would ordinarily be the flesh side, and allowing the ink to flow around the edges while protecting the opposite, display or grain side from the ink by holding it against a clean surface.

One object of the invention is to still further improve the above-described Bazzoni method of inking edges to the end that the danger of smooching the display surface of the part is eliminated.

From one aspect, the improved method resides in protecting the finished surface by holding it in contact with the nap surface of a piece of suede-leather-like material as ink is applied to the other surface and the edges of the shoe part.

Still another object of the invention is to provide an improved machine by which the novel method may be readily carried out.

A feature of the invention is to be found in the provision of a protective piece of suede-leather-like material which is illustrated as supported on a rigid roll and against the velvety or nap surface of which the display side of a piece of work is held. As herein illustrated and in accordance with other features of the invention, the suede protector is in the form of an endless belt and the work is carried between this belt and an absorbent applying roll by an articulated carrier of soft fibered, pervious material, such as cheesecloth. Also as illustrated, provision is made for wringing the surplus ink from the suede belt to take care of that portion of the coating material which has been applied thereto beyond the periphery of the work piece.

These and other features of the invention will

be described in the following specification, taken in connection with the accompanying drawings, in which

- Fig. 1 is a side elevation of the machine;
5 Fig. 2 is an end view of the supporting and applying rolls on a larger scale;
Fig. 3 is a longitudinal, vertical section through the midpart of the machine;
Fig. 4 is a view, much exaggerated, showing the 10 point of contact between the supporting and applying rolls, a piece of work having a cut-out opening being interposed between them;
Fig. 5 is a plan view with upper parts broken away, and
15 Fig. 6 is a perspective view of a piece of work.
On a supporting base 10, a frame 12 is provided on which there is carried a receptacle 14 containing coating material 16 (Fig. 3). On this receptacle, bearings are provided for a rigid supporting roll 20, a resilient and preferably absorbent applying roll 22 of some bibulous material, such as felt, and a pick-up roll 24 which dips in the coating material 16 and delivers it to the applying roll. The arrangement is such that pieces of work 20 are presented to the bite of the rolls 20 and 22 by a carrier belt 26 traveling over supporting rolls 28 and 30 and passing under the roll 20 and over the roll 22. The belt roll 28 is adjustable to tension the belt. This carrier belt is reticulated to 30 enable the coating material to pass through its meshes into contact with the back or flesh surface 32 of a piece of work W (Fig. 4). For the best operation, this carrier belt 26 should be made of pervious, soft-fibered material, one excellent example of which has been found to be ordinary cheesecloth. Experience has shown that hard-fibered, nonabsorbent materials do not permit the passage of ink as readily.

- Surrounding a large part of the periphery of 40 the rigid supporting roll 20 is a work protector of velvety material, here shown as an endless belt 34 of suede leather positioned with its rough, fibrous, nap surface outside for engagement with the work. As the piece of work is pressed lightly 45 into the nap or pile of this suede belt 34, a complete protection is provided for the finished or grain surface 36 of the work, which is held smoothly without undue pressure in contact with this suede surface. The reason for this protective action is not fully understood. It may result from the absorbent character of the nap surface of the suede leather or it may result from the retarding effect of the forest of upstanding fibers closely adjacent to the edges of the work. 55 Ink received from the applying roll 22 will pass

through the interstices of the carrier belt 26 and beside being applied to the whole of the unfinished or fresh surface 32, will flow around the edges of each piece of work W, regardless of whether these are peripheral edges 38 or the edges of cut-out openings 40. At the same time, a considerable quantity of ink will necessarily be applied to the protective suede belt 34, as to those portions which are not covered by a piece of work, and in order that there may not be an undue accumulation of such ink in this belt, the machine has been provided with a wringer, here shown as coacting rolls 42, 44. These rolls are mounted for free rotation in a pair of frame arms 46 interconnected by a web 48 and integral with bearings 50 which are provided for the shaft 52 of the supporting roll 20. These bearings and the bracket arms 46 are slidably mounted upon guide ribs 54 on the upper edges of the receptacle 14 and the whole assembly, comprising the supporting roll 20, the suede belt 34, the bracket arms 46 and the bearings 50, is urged toward the applying roll 22 by springs 56. The springs 56 are joined to bolts 60 and the tension of the springs may be adjusted by nuts 58 threaded on the bolts 60 and resting against lugs 62 formed on the outer sides of the receptacle 14. A trough 64 is provided beneath the wringer rolls 42, 44 and coating material removed from the suede belt by the wringer rolls is conducted through a pipe 66 back into the receptacle 14.

Rotation of the work-engaging rolls 20 and 22 is effected by a sprocket chain 10 which is guided over a sprocket on the roll 20 and under a sprocket on the roll 22 and is driven by a sprocket 12 which derives power through a speed-reducing gearing 14 from a power-driven pulley 16. The chain is also guided around a fixed idler 18 and a spring-tensioned idler 20 which keeps it tight. The sprockets on the rolls 20 and 22 are so designed that the surface speeds of these rolls are identical so that there is no slippage between them. Friction between the carrier 26 and the rolls 20 and 22 is sufficient to keep this carrier moving at the same speed as the surface speed of said rolls.

An exact control of the quantity of ink applied by the felt roll 22 is secured by making the bearings 82 of the pick-up roll 24 slidable in grooves in the sides of the receptacle 14. These bearings are then urged upwardly by springs 84, the tension of which is adjustable by screws 86.

In the operation of the machine to carry out the novel method, pieces of work W of any contour are laid on the horizontal run 90 of the pervious or reticulated carrier belt 26. By this carrier belt, each piece is held with its finished or grain surface 36 firmly in contact with the suede belt 34 where the latter is wrapped around the rigid supporting roll 20. At the bite of the rolls 20 and 22, ink will be squeezed out of the applying roll 22 and applied not only to the whole of the opposite surface 32 of the work but will also be caused to flow into contact with the peripheral edges 38 or the edges 40 of cut-out openings. This ink, the quantity of which may be accurately controlled by the screws 86, will not be in sufficient quantity to soak through the pieces of work W but will pass freely through the soft-fibered, reticulated carrier 26 to coat the edges 38 and 40. Variations in the thickness of the work are accommodated partly by the compressibility of the felt roll 22 and partly by the yielding of the springs 56. It will be realized that in order for this operation to be successful, the ink must not pass around from the edges 38 and 40 on to

the finished surface 36 and to this end, the suede leather of the belt 34 is unusually successful. The pressure between the rolls 20 and 22, effected by the adjustable springs 56, is relatively light, being a matter of ounces rather than pounds. After the pieces of work leave the bite of the rolls, they pass along a downwardly inclined run 92 of the carrier belt 26 and are picked up by a scraper blade 94 and passed on to a table 96, from which they may be removed by the operator.

The ink applied by the roll 22 is to that face of the work which is to be concealed in the finished article and which has been described in the specification as the flesh surface of the work. On the other hand, the surface which is protected by the suede leather has been referred to as the display, finished or grain surface of the work. It will be understood, however, that this is merely the most typical example and that the method and machine are equally applicable in an instance in which it is desired to apply the ink to the grain surface and edges of a piece of leather, provided the flesh surface is the one which is to be exposed in the finished article.

Having described my invention, what I claim as new and desire to secure by Letters Patent of the United States is:

1. The method of applying ink to the edges of a shoe part which consists in pushing one side of the shoe part into the nap of a piece of suede-like material, and applying sufficient ink to the other side of the shoe part to cause the ink to overflow and coat the exposed edges, the first-mentioned side being protected from the ink by the suede-like material.

2. The method of coating the edges of a shoe part which consists in holding one surface of the shoe part in contact with a piece of suede-like material, applying pressure to the opposite side of the shoe part, and simultaneously applying sufficient ink to said opposite side to cause it to overflow the exposed edges of the shoe part.

3. The method of coating the edges of a shoe part which consists in supporting the part with one surface in contact with a reticulated carrier, holding a piece of suede leather with its nap surface in contact with the other surface of the shoe part, and squeezing ink through the reticulations of the carrier into contact with the first-mentioned surface and edges of said part while the other surface thereof is protected by the suede.

4. In a machine for coating the edges of shoe parts, coacting rolls, a suede-like covering for one of said rolls having the nap projecting outwardly therefrom, and means for supplying ink to the other roll for transfer to one surface and the adjacent edges of a piece of work, the other surface of which is supported by the suede-covered roll.

5. In an inking machine for coating the raw edges of a shoe part, a supporting roll, an ink-coated applying roll coacting therewith, a carrier of soft-fibered, pervious material interposed between said rolls, and a piece of suede leather surrounding the supporting roll with its nap directed outwardly toward the carrier, said applying roll being compressible thereby to squeeze ink on one surface and the edges of the work as a piece of work is passed between the carrier belt and the suede leather piece while the other surface thereof is protected from the application of ink by the suede leather.

6. In an inking machine for coating the raw edges of a shoe part, a carrier belt of soft-fibered,

pervious material, an absorbent, resilient applying roll positioned at one side of said belt, means for supplying ink to said roll, a supporting roll coacting with said applying roll and positioned on the other side of the belt, an endless suede belt surrounding said supporting roll with the loose fibers of the nap of the suede projecting toward the carrier belt, and means for holding said supporting roll and applying roll in close relation such that a piece of work on the carrier belt will distort the applying roll whereby ink is squeezed through the belt on to one surface and the edges of the work, the other surface being protected by the suede belt.

7. In an inking machine having coacting applying and supporting rolls, an endless belt of suede-like material surrounding the supporting roll, nap side out, for contact with one surface of a piece of work, the other surface of which is coated by the applying roll, and means for removing surplus ink from the suede belt.

8. In an inking machine having coacting supporting and inking rolls, an endless suede belt surrounding the supporting roll, and a wringer for removing surplus ink from the suede belt.

9. In an inking machine, a receptacle, a rigid roll, a suede belt surrounding said rigid roll, a wringer for removing surplus ink from the suede belt, means for conducting said surplus ink back to the receptacle, an applying roll coacting with the suede-covered rigid roll, and means for supplying ink from the receptacle to the applying roll.

10. In an inking machine, a carrier belt of reticulated material, means for supporting said belt arranged to provide a substantially horizontal work-receiving run, a compressible applying roll, a supporting roll positioned substantially horizontally opposite to the applying roll and just above one end of said work-receiving run and

around a portion of which the carrier belt is wrapped as it is guided over the applying roll, and a suede covering for the supporting roll.

11. In an inking machine, a support, an applying roll, a member mounted for adjustment toward and away from the applying roll, a rigid supporting roll rotatable thereon, an endless belt surrounding said supporting roll, wringer rolls positioned on said member for removing surplus ink from the belt, a spring for moving the member toward the applying roll, and means for adjusting the tension of the spring.

12. In an inking machine, a felt applying roll, means for supplying ink thereto, a coacting, rigid, supporting roll, the operative portion of which is surrounded by a piece of suede-like leather with its nap surface facing the applying roll, a carrier belt of cheesecloth-like material passing between said rolls, and means for tensioning said carrier belt to cause it to hold a piece of work smoothly in contact with the nap surface of the leather around the supporting roll.

13. In an inking machine, a receptacle, applying and supporting rolls positioned above the receptacle and movable relatively, adjustable spring-tension means for causing the approach of said rolls, an endless carrier belt passed between said rolls and wrapped around a portion of the periphery of each, and means for driving said coacting rolls at substantially equal peripheral speeds.

14. In a machine for applying ink to the edges of a shoe part, means for pushing one side of the shoe part into the nap of a piece of suede-like material, and means for applying sufficient ink to the other side of the shoe part to cause the ink to overflow and coat the exposed edges, the first-mentioned side being protected from the work by the suede-like material.

VALENTINE F. HARRINGTON.
